(57) **CLAIM**

The ornamental design for a charging cable, as shown and described.

DESCRIPTION

FIG. 1 is a perspective view of a charging cable of the present invention.

FIG. 2 is a front elevational view of the charging cable of FIG. 1.

FIG. 3 is a rear elevational view of the charging cable of FIG. 1.

FIG. 4 is a left side elevational view of the charging cable of FIG. 1.

FIG. 5 is a right side elevational view of the charging cable of FIG. 1.

FIG. 6 is a top plan view of the charging cable of FIG. 1; and,

FIG. 7 is a bottom plan view of the charging cable of FIG. 1.

1 Claim, 7 Drawing Sheets
